UNITED STATES PATENT OFFICE.

CARL D. FISCHER, OF WAPAKONETA, OHIO.

VEHICLE-HUB.

SPECIFICATION forming part of Letters Patent No. 650,932, dated June 5, 1900.

Application filed October 6, 1899. Serial No. 732,751. (No model.)

To all whom it may concern:

Be it known that I, CARL D. FISCHER, a citizen of the United States, residing at Wapakoneta, in the county of Auglaize and State 5 of Ohio, have invented certain new and useful Improvements in Vehicle-Hubs; and I do hereby declare the following to be a full, clear, and exact description of the invention, such as will enable others skilled in the art to which 10 it appertains to make and use the same.

My invention relates to that class of metal hubs having mortises designed to receive wooden spokes having their inner ends provided with tenons fitting in the mortises and 15 for use especially in automobiles, but adapted also to other vehicles requiring strong and symmetrical hubs.

The special object of my invention is to provide a compact and strong solid metal hub, 20 as an article of manufacture, having circumferential flanges of great strength for guarding and supporting the inner ends of the spokes, the latter being provided with tenons to fit into mortises between the flanges.

25 The invention consists in the construction hereinafter described, and defined in the claims.

The accompanying drawings represent, in Figure 1, a side of the hub; in Fig. 2, a cross-sectional view, taken on line 2 2, Fig. 1, through the hub at one side of the inner ends of the spokes, the latter being partly sectional; in Fig. 3, a longitudinal section of the hub on line 3 3, Fig. 1, showing the shape of the 35 interior or axle-box.

The hub A is made with a series of separate mortises B around its central exterior, just far enough apart to allow the inner ends of the spokes to be assembled and be in close 40 contact with each other when their tenons are resting in the mortises B, there being a substantially-solid mass of metal C yet beneath the inner ends of the mortises.

The circumferential flanges D extend outward from the hub at the ends of the mortises for forming side supports to the inner ends of the spokes and are provided with holes, as is usual, for the passage of bolts when the spokes have had their tenons inserted in the sockets or mortises. The ends 45

55 E and F or rim ends of the hub extend from the outer portions of the interior strengthening mass of metal C, as shown in Fig. 3, presenting a longitudinal section of axle-box. It will thus be seen that the hub's interior at 60 each of its ends is enlarged and that notwithstanding the rim ends of the hub are of sufficient substance for required strength the symmetrical proportions of the hub in its entirety having regard, withal, for solidity and 65 strength where the latter is specially required, are features of construction of a notably meritorious character in an integral metallic hub.

The circumferential flanges D having their 70 bases involved or arising from and strengthened by the mass of metal C and continuing from that immediately beneath the mortises affords strong and durable side supports for the inner ends of the spokes, and the general interior shape of the hub adapts it for ready application to axles, while the exterior configuration presents features of utility, 75 strength, and symmetrical proportions.

The hub may be made of any kind of metal, 80 but is preferably a malleable-iron casting.

Hubs have been formed entirely of metal and embodying constructions adapted for receiving the inner ends of spokes, tenons and mortises being sometimes provided, and 85 metal flanges for side support of the spokes being sometimes formed on parts of certain metallic attaching parts, and in some cases hubs have been cast of metal in a single piece, with circumferential flanges adjacent 90 to a series of sockets or mortises, the latter having their inner ends connecting with each other in an annular space. Rods or bolts are commonly used to pass through said metal flanges and through openings formed by half-round notches in the adjacent sides of the 95 inner ends of the spokes.

No hub, so far as I am aware, has been made of solid metal throughout having mortises or sockets of complete inner closure for receiving spoke-tenons and having circumferential flanges immediately adjacent to and extending out beyond the mortises and having an interior of a substantial strengthening mass of metal beneath the mortises, being a 100

solid or integral hub with a hollow interior forming the axle-box.

Having described my invention, what I claim as new, and desire to secure by Letters 5 Patent, is—

1. A solid metallic hub composed of integral parts, having an axle-box, a circle of mortises with closed inner ends to receive tenons or spokes, circumferential flanges 10 adjacent to and extending out beyond said mortises and provided with suitable holes for bolts, substantially as and for the purpose described.

2. As an article of manufacture, a solid 15 cast metallic hub, having an axle-box of diminished interior at the center to afford a strengthening mass of metal C, a series of mortises B, in the exterior and opposite there-to, and circumferential flanges D, adjacent

to and extending out beyond said mortises, 20 substantially as and for the purpose described.

3. A solid cast metallic hub having an axle-box, a series of separate mortises closed at their inner ends, circumferential flanges D, on its exterior, adjacent to and extending out 25 beyond said mortises and provided with bolt-holes, in combination with spokes having tenons, in the mortises, and transverse grooves, forming holes between adjacent spokes, and bolts passing through said latter holes and 30 the holes in the flanges, substantially as described.

In testimony whereof I affix my signature in presence of two witnesses.

CARL D. FISCHER.
